CLAIM

The ornamental design for a belt accessory system, as shown and described.

DESCRIPTION

FIG. 1 is a front perspective view showing a belt accessory system of the new design in a position of use proximate to a belt;

FIG. 2 is a front perspective view showing an inner belt of the belt accessory system of FIG. 1;

FIG. 3 is a top plan view of the inner belt of FIG. 2;

FIG. 4 is a front elevation view of the inner belt of FIG. 2;

FIG. 5 is a bottom plan view of the inner belt of FIG. 2;

FIG. 6 is a right side cross-sectional view of the inner belt taken along line 6-6 of FIG. 4;

FIG. 7 is a left elevation view of the inner belt of FIG. 2; and,

FIG. 8 is a rear elevation view of the inner belt of FIG. 2. The broken lines in the drawings illustrate the portions of the belt accessory system or environmental structure that form no part of the claimed design.
